UNITED STATES PATENT OFFICE.

JULIUS STIEFEL, OF BALTIMORE, MARYLAND.

BIFURCATED GARMENT.

SPECIFICATION forming part of Letters Patent No. 375,219, dated December 20, 1887.

Application filed October 4, 1887. Serial No. 251,443. (No model.)

To all whom it may concern:

Be it known that I, JULIUS STIEFEL, a citizen of the United States, residing at Baltimore, in the State of Maryland, have invented 5 new and useful Improvements in Bifurcated Garments, of which the following is a specification.

The object of my improvement is to prevent the tearing of the drawers at the crotch or end 10 of the front opening. For this purpose re-enforcing cross-strips of unyielding material have been applied at the crotch, so that the tearing force is exerted at this point upon the strip crosswise of its width, which thus forms 15 a stay at the point where the force is exerted. Such resistance, however, is principally upon the stitching and that due to the cross-grain and width of the stay, and while it gives better protection than ordinary fold binding and 20 stitching, yet I have found such cross-stay insufficient for the purpose, and it also renders the garment of undesirable thickness and set at this point.

My improvement while forming an effective 25 stay at the crotch of the garment forms also a neat set at the end of the opening, and its construction is such that the strain at the crotch of the garment is not resisted in a direction crosswise at the end of the opening, but in the 30 line of the edges of the opening, so that when the fronts of the garment are opened the pulling force will be exerted in a line along the edges of both sides and not crosswise at the crotch, and thus absolutely prevent the tearing 35 of the garment at the crotch.

Referring to the drawings, Figure 1 represents in front view a pair of drawers having my improved way of re-enforcing the front opening thereof. Fig. 2 is a view showing the 40 direction of a pulling strain at the crotch when the fronts are fully open. Fig. 3 is a detail sectional view of the crotch-stay; and Fig. 4 shows a portion of my improved cord crotch-stay as prepared with a cover by which the 45 stay-cord is applied to the drawer-fronts.

The body *a* and the waistband *b* of the drawers may be made in the usual way, as shown, or in any other suitable manner. As shown, the waistband extends around the sides of the 50 front opening, as re-enforcing fronts *c*, and are stitched together at the crotch in the usual way.

My improvement is a separate edge-binder forming a continuous stay around the edges of the front opening of the garment and crossing 55 the seam-joint crotch with a neat set at *e*. This stay I form as a separate device and apply as follows: A piece of unyielding cord or other material, *m*, Fig. 4, of the desired kind, and of a length sufficient to extend entirely around the 60 edge of the front opening from the waistband corners *n*, is covered with a cotton strip, so as to give it a cord edge, *g*, and a webbing part, *h*, in the manner of what is known as "piping" or "cording," as shown in Fig. 4. This unyielding cord-bound strip, by its web *n*, I then sew in between the folded front edges, *i*, of the drawer-fronts, *c*, and the folded front edges, *c*, of the waistband-fronts are seen at the broken-seam part in Fig. 1, thus making this sewed 70 part support the covered cord *m* outside of the stitching and thus give to each drawer front a cord finish, so that the strain at the crotch is resisted in the length of the cord along the edge and it cannot tear. It cannot break, and 75 there is no strain upon the stitching, because the stitching is behind the cord-bound part and is therefore protected by it at the crotch.

While my improvement gives most effective 80 security against tearing at the crotch of the drawers, it also gives a neat edge finish; and for this purpose I prefer to extend the cord all around the edge of the front opening; but it may only extend around the crotch part to protect it, as stated.

I have shown the cord-bound stay as applied 85 to the drawer-fronts; but it may be applied to the back opening and to any garment having an open part liable to tear when stretched.

I am aware that re-enforcing stay-pieces, both 90 corded and folded, have been used for bifurcations in garments, in which the stay has been applied both to the surface of the goods and between the folds or double parts thereof directly across the crotch or end of the opening 95 and secured by stitching in the garment on each side of the crotch in such manner that the spreading strain upon the parts tends to pull the stay away from its stitching and to pull the stay out of its place in the garment 100 and therefore to break its stitching. In my construction the re-enforcing stay forms an exposed supplemental edge all around the bifurcation, so that the spreading strain is not

upon the stitching nor upon the garment, but upon the supplemental edge of the garment in the direction of the length of such edge, whereby the garment is so stayed all along this edge as to practically transfer the spreading strain from the crotch of the open parts to the whole length of the open parts. In this particular my improvement gives the advantage of supplementing the edge of the fly or opening with an external stay crossing the crotch or junction of the parts of the opening, so as to practically isolate the garment parts from the spreading strain at the crotch. In this particular the function of the external edge stay is essentially different from the function of a stay loosely crossing the crotch in the opening, or an interior cross stay receiving the spreading strain and transferring it to the garment parts and tending to pull it from its stitching therewith.

I claim—

1. A pair of drawers or similar garment

having the edge of the bifurcated part re-enforced by a cord-bound stay composed of an unyielding cord and a binding fabric strip bound by its web between the garment parts along the edge thereof, and supplementing the edge at the junction of the stayed parts in a manner to relieve the latter of strain, as herein set forth. 39

2. As an improved article of manufacture, a pair of drawers having the front edge of the fly-opening supplemented by an unyielding cord-bound stay crossing the crotch of said opening and transferring the spreading strain from the garment to the projecting edge stay thereof, substantially as shown and described. In testimony whereof I have hereunto set my hand in the presence of two subscribing witnesses.

JULIUS STIEFEL.
